UNITED STATES PATENT OFFICE.

ADDISON N. CALKINS, OF QUINCY, ILLINOIS, ASSIGNOR TO ELECTRIC WHEEL COMPANY, OF QUINCY, ILLINOIS, A CORPORATION OF ILLINOIS.

TRACTOR.

Application filed December 21, 1925. Serial No. 76,591.

- The invention pertains to tractors having an endless chain or belt consisting of a series of separate link sections pivotally connected together so as to travel around spaced rotary supporting members and coacting to restrain flexing in an upward direction as the chain travels over the ground but permitting a bending or flexing of the chain around the supporting members.
- 5 The object of the invention generally stated is to produce a chain for a tractor of the character referred to in which the link sections are operatively connected together in a novel and advantageous manner to produce 10 between adjacent links a truss action preventing flexing of the chain upwardly as it passes over the ground, but permitting relative pivotal movement between the sections for passage around the supporting members.
- 15 In attaining the object thus set forth I provide separate sections adapted to be operatively connected by links or bars in a manner such that a truss is formed between each pair of adjacent sections. Each section is provided with a rigid tapered arm construction lying in the plane of the chain sections. The arms of adjacent sections are interconnected by a lost motion construction 20 which limits flexing of the chain to a single direction out of the plane of the treads of the sections. The aim is to simplify the construction of the chain while imparting strength and durability thereto.
- 25 In the accompanying drawings, Figure 1 is a fragmentary side elevational section of a tractor illustrating my invention in its preferred form.
- 30 Fig. 2 is a fragmentary horizontal section taken approximately in the plane of line 2-2 of Fig. 1.
- 35 Fig. 3 is a fragmentary inner plan view showing two link sections connected together.
- 40 Fig. 4 is a fragmentary vertical sectional view taken approximately in the plane of line 4-4 of Fig. 3.
- 45 Fig. 5 is a transverse sectional view taken in the plane of line 5-5 of Fig. 4.
- 50 Fig. 6 is a perspective view of one of the link sections.
- 55 While the invention is illustrated in its preferred form it is contemplated that various changes in the construction and arrangement illustrated and hereinafter described may be made by those skilled in the art without departing from the spirit and scope of the invention as expressed in the appended claim.
- The tractor comprises generally a central frame member 10 elongated in form and providing bearings at opposite ends in which are journalled the axles 11 of two pairs of rotary supporting members or wheels 12. The frame member is mounted substantially midway between its ends to turn on a shaft 13 upon which the tractor frame proper may be supported in the usual way.
- The endless belt or chain is composed of a plurality of similar sections each comprising a tread portion or shoe 14 generally rectangular in form and of substantial width. Extending inwardly from this shoe is a frame structure preferably formed integral with the shoe and comprising a pair of inclined arms 15 and a pair of inclined arms 16 projecting inwardly of the section. Each set of arms 15 merge with the opposite arms 16 forming in effect flat tapered arms designated 18 and 19, which are spaced apart in parallel relationship in the plane of the chain. The apexes of the tapered arms are herein positioned centrally of the chain section and each is provided with a hole 20 through which a pivot bearing or bolt 21 is fixed. The outer part of each arm at some point intermediate the hole 20 and the section tread 14 contains another hole 22 which is herein shown in line with the first hole perpendicular to the tread. A second pivot bearing or pin bolt 23 is contained in the second hole.
- Adjacent shoes are hinged together to form the chain. For the hinging joint there are formed interlocking bars on the shoes, there being three on one edge as 24, 25 and 26, and two on the other edge as 27 and 28 which fit snugly into the two spaces between the three aligned bearings 24, 25 and 26. A pivot pin 29 passing through the aligned bearings serves to connect the tread portions of the adjacent link sections together. To hold the pivot pin 29 in place, each of the end bearings has formed at its inner end a pair of lugs 30 disposed on opposite sides of the bearing apertures which lugs are themselves apertured to receive a retaining pin 31. For convenience and for the purpose of providing a rigid construction the arms 16 terminate in the bearing 25 while arms 15

rise from the ends of the bearings 27 and 28, the arms 15 being slightly more separated at the bottom than at the top to provide for receiving the bearing 25, and also the arms 16 as the adjacent treads pass around the wheels.

At opposite sides of the shoe are formed track portions 32 the forward ends of which are constructed so that they are coextensive 10 with the respective bearings 24 and 26. The track portions are preferably cored out as indicated at 33 (Fig. 6) to lessen the weight of the section. Suitable reinforcing ribs 34 may be provided on the inner 15 face of the shoe 14 as clearly indicated in Fig. 6.

In addition to the pivotal connection thus provided between tread portions of the link sections there is provided a connecting bar 20 or link 35 having one end pivotally mounted on the pivot bolt 21 of one section and its other end pivotally mounted on the pivot pin 23 of the next or rearwardly adjacent section. Thus the bar is angularly disposed 25 with respect to the tread portions of the link sections. The bar 35 is a simple link positioned between the spaced arms of adjacent shoes. One of the desired features 30 of the present invention is to use a link which is straight and not bifurcated. For this reason, corresponding pivots of adjacent sections are not joined by the link, the two pivots 21 and 23 being provided to permit this construction. The inner end 35 swings on its pivot 21 while the outer end slides on its pin 23 there being a slot 36 in this end. The position of the extreme end of the slot 36 relative to the pivot center of bolt 21 is such that the bar acts as a limiting 40 means to prevent hinging of the adjacent shoes beyond the plane of the shoe treads, Fig. 4 showing the parts occupying the limiting position. However, the links of the chain are free to hinge in the other direction 45 so that the chain may freely pass around the wheels 12.

To guide the link sections around the rotary supporting members 12, the track portions 32 of each section are provided 50 with inwardly extending flanges 37 at the inner edges of the track portions; and to cause the link sections to adhere snugly to the peripheries of the supporting members as they pass around them, means is provided operating to maintain the chain under 55 tension. Thus the axle 11 for one pair of supporting members 12 is mounted in a movable bearing 38 slidably in a bearing box 39, Fig. 1, at one end of the frame mem-

ber 10. The latter has an opening 40 there- 60 in at one end in which is mounted a screw 41 having an adjusting nut 42 thereon between which and the bearing 38 is inter- 65 posed a coiled spring 43, the latter passing through a suitable opening in one side of the bearing box. This construction while operating to maintain the chain taut serves to reduce noise produced by the links passing around the supporting members and also prevents injury to the parts by permitting 70 one of the bearing members to yield relative to the other in the event that a stone or other substance should find its way between the supporting members and the chain. 75

It will be seen that in the plane relation of the chain sections adjacent shoes 14, their legs 15 and 16, and the connecting bars 35 form a truss member rigid against flexure in one direction. The arrangement of 80 the parts in the manner described provides for a simple mechanical construction of the chain sections which affords great strength in the truss and which permits a compact assembly of the parts so that in the 85 curved relation there is no interference between the adjacent moving members.

I claim as my invention:—

An endless chain of the character described having a series of link sections each 90 comprising a tread portion with spaced pivot bearings along opposite edges whereby the tread portions of adjacent sections may be pivotally connected together, each of said tread portions having an inwardly 95 projecting tapered arm structure composed of two spaced parallel arms and having its apex disposed substantially centrally of the section, two pivot bearings in each arm structure alined centrally of the tread portion 100 and having pivot pins therein, one of said pivot bearings being located substantially at the apex of the arm structure, and the other spaced substantially midway between the apex and the tread portion; and a connecting bar pivoted substantially in the apex 105 of the arm structure of one of said link sections, said bar extending between the parallel arms of an adjacent link section and pivoted thereto at a point below the apex thereof, one end of the bar having a slot 110 therein adapted to permit relative hinging movement of the link sections in one direction, but to prevent such movement in the other direction.

In testimony whereof, I have hereunto affixed my signature.

ADDISON N. CALKINS.
